CLAIM

The ornamental design for a portable toilet as shown and described.

DESCRIPTION

FIG. 1 is a front view of a portable toilet showing a first embodiment of my design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front, right, top perspective view thereof;

FIG. 8 is a rear, left, top perspective view thereof;

FIG. 9 is a rear, right, bottom perspective view thereof;

FIG. 10 is a front view of a portable toilet showing a second embodiment of my design;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a front, right, top perspective view thereof;

FIG. 17 is a rear, left, top perspective view thereof; and,

FIG. 18 is a rear, right, bottom perspective view thereof.

For the second embodiment, the only difference from the first embodiment is the configuration of the press-button as shown on the top, right side of FIG. 11, and it is understood that all other surfaces are the same as those of the first embodiment.
